DESIGN FOR A LACE YOKE FOR A NECK PIECE FOR WOMAN'S GARMENT OR SIMILAR ARTICLE

Application filed June 27, 1932. Serial No. 44,202. Term of patent 3½ years.

To all whom it may concern:

Be it known that I, NATHAN KLEIN, a citizen of the United States, residing in the city of Newark, county of Essex, and State of New Jersey, have invented a new, original, and ornamental Design for a Lace Yoke for a Neck piece for Woman's Garment or Similar Article, of which the following is a specification, reference being had to the accompanying drawing forming part thereof.

The figure of the drawing is a plan view of the lace yoke showing my new design. The opposite half of the lace yoke illustrated in outline is the same as that illustrated in detail.

I claim:

The ornamental design for a lace yoke for a neck piece for woman's garment or similar article substantially as shown and described.

NATHAN KLEIN.
